UNITED STATES PATENT OFFICE.

GEORGE R. LE SAUVAGE, OF OAK PARK, ILLINOIS, ASSIGNOR TO SOLAR-STURGES
MFG. CO., A CORPORATION OF ILLINOIS.

DESIGN FOR A COVER FOR WASTE RECEPTACLE OR SIMILAR ARTICLE.

Application filed June 23, 1924. Serial No. 9,947. Term of patent 14 years.

To all whom it may concern:

Be it known that I, GEORGE Ross LE SAUVAGE, a citizen of the United States, and residing at Oak Park, in the county of Cook and State of Illinois, have invented a new, original, and ornamental Design for a Cover for Waste Receptacle or Similar Article, of which the following is a specification, reference being had to the accompanying drawing, forming a part thereof.

On the drawing:

Figure 1 is a plan view of the waste receptacle cover showing my new design.

Figure 2 is a side elevation of the waste receptacle cover shown in Figure 1.

I claim:

The ornamental design for a cover for waste receptacle or similar article as shown,

GEORGE R. LE SAUVAGE.
